WALTER H. PHELPS, OF NEWARK, NEW JERSEY.

BUTTON AND PIN THEREFOR.

1,310,804.

Specification of Letters Patent.

Patented July 22, 1919.

Application filed June 12, 1918. Serial No. 239,615.

To all whom it may concern:

Be it known that I, WALTER H. PHELPS, a citizen of the United States, and a resident of Newark, county of Essex, and State of New Jersey, have invented certain new and useful Improvements in Buttons and Pins Therefor, of which the following is a specification.

This invention relates to buttons such as 10 are adapted to be attached to garments for display purposes or to be used as badges or the like.

The invention has for its object the provision of such a button, badge or the like, and 15 a pin therefor, which can be simply, cheaply and easily manufactured and assembled and which, when attached in garments, as to a coat lapel, will be securely locked and held and will remain substantially permanently 20 in place until intentionally removed.

In the accompanying drawing forming part of this specification, Figure 1 is a face view of one form of button embodying the present invention. Fig. 2 is a rear view of 25 the button shown in Fig. 1. Fig. 3 is a cross-sectional view on lines 3, 3, Figs. 1 and 2. Fig. 4 is a top view. Fig. 5 is a rear face view of the pin, and Fig. 6 is a top view of the pin.

30 The button portion may be of any construction so long as it has an inturned flange about the rear face. Buttons in accordance with the invention are usually circular in outline, but may be of other forms. In the 35 drawings I have illustrated the ordinary type of "celluloid" button which comprises a metallic shell, preferably domed somewhat and indicated by reference numeral 10, with a covering of flexible transparent material, such as celluloid, indicated by the 40 numeral 11. This celluloid covering is made somewhat larger than the shell 10 and has its edges turned inward thereover, and a metallic ring 12 is inserted to hold the edges 45 of the celluloid covering 11 in place. The display may be printed either directly on the metallic disk 10 or printed on paper or the like interposed between the shell 10 and the celluloid covering 11, as is customary. 50 In the type of button shown, the inwardly

projecting annular flange 13 is formed on the annular ring 12, but as above stated, other forms of button may be used so long as they have an inturned flange on the rear face thereof, and that shown is for purposes 55 of illustration only and not for limitation of the invention.

The pin is designated in general by reference numeral 14 and is inserted within the flange 13. It is preferably made of wire or 60 similar material and comprises a principal portion 15 of generally part-circular form, but being adapted, when uncompressed, to spring outwardly substantially as shown in Fig. 5 in full lines, the dotted line 16 illustrating the position to which it is forced upon insertion within the flange 13. Such main portion 15 makes up preferably more 65 than half a circle as shown, so as to bring the pin portion proper, designated by reference numeral 17, across the back of the button, at a substantial distance from the center, forming the segment of an arc which is less than a semi-circle. The portions 15 and 17 are joined in a smoothly rounded 70 curved portion 18 so that the pin portion 17 may be moved or turned relative to the portion 15 which remains substantially stationary within the button flange without 75 danger of breakage or of taking a permanent set. As will be clear from Fig. 5, the pin portion 17, as formed, tends to 80 spring with its point 19 away from the portion 15, and it is so constructed in order to give it one of two tensions which are of importance in the operation of the button. Also it appears from Fig. 6 how the pin is 85 bent so that the point 19 tends to stand away rearwardly from the portion 15 and out of the plane thereof, which is done in order to 90 give the pin a second tension, as will be further referred to.

In Figs. 1 and 2 the pin is illustrated in the locked position which it occupies when the button is in place on a garment or the 95 like, the point 19 of the pin being caught, held and locked under the inturned flange 13. The position occupied by the pin portion 17 before being fastened or locked in place, is indicated in dotted lines at 20, Fig. 2, and 100

the position to which the pin portion 17 is forced in order to admit the point 19 thereof under the flange 13, is illustrated in dotted lines at 21. The tension on the pin 5 which tends to project the pin portion 17 from the inserted portion 15, causes the pin portion 17 normally to take up the position indicated at 20. To place it on a garment, after the pin has been passed through the 10 material and out again, the portion 18 is forced inwardly to substantially the position shown in dotted lines at 21, and such pin is then permitted to expand, the point 19 having first been thrust inwardly toward the face 15 of the button, and the expansive action of the pin when released carries the point 19 under the flange 13, and it is obvious that the same will remain so held and locked unless positively pushed in the direction indicated by the arrow 22 in Fig. 2. Fig. 3 20 shows how the point 19 is held by the second of the two tensions on the spring firmly against the under side of the flange 13, whereby the locking action is made more 25 secure and effective. The locked position of the pin within the button is illustrated in Fig. 4 in full lines, and the position normally occupied by the pin before being inserted within the flange 13 of the button, is 30 indicated in dotted lines in said figure and is designated by reference numeral 23.

The entire pin member 14 may, of course, be rotated within the button so as to bring the pin portion 17 across the same at or toward substantially the top thereof as is illustrated in Figs. 1 and 2, whereby the button 35 may easily be placed in correct position so that printed matter or the like thereon may be erect and easily read.

40 The pin portion 17 is illustrated with an offset at the parts 24 and 25 thereof, and I prefer to give such pin portion 17 more or less rearwardly directed offset intermediate its ends as illustrated, for example, in Figs. 45 4 and 6. However, such rearward offset is not entirely essential and may be dispensed with if desired, or may be greater or less than as illustrated.

It will be seen that buttons and pins therefor, embodying the present invention, may 50 be simply and cheaply constructed, as the same may be entirely completed with ordinary dies without any special or particular provisions for adapting the pin for use with 55 the button. The assembly is simply and easily made by merely contracting the pin portion and inserting it within the button back and allowing it to expand, and when the pin is placed in the button for assembly, 60 the point 19 may also be inserted within the button back as shown in Fig. 2, thus avoiding any scratching or marring of the button faces or the like which might be caused by a freely projecting pin point, as, for example,

when a quantity of the buttons are simply 65 thrown loosely into a container as is the usual and most convenient mode of packing. The pin portion 17 being away from and of less length than the diameter of the button, and arranged to extend across the same at 70 substantially an arc less than a diameter, makes it possible for the pin point 19 to be inserted under the flange 13 in the manner shown and described, and by providing the two tensions which have been referred to, 75 the pin portion 19 is firmly and securely held and locked in place, since one of the tensions pushes the pin toward the arc whose segment is formed by the pin portion 17 and therefore firmly against the interior of the 80 channeled portion of the button, and the second tension acts to force the pin point 19 firmly against the under side of the inturned flanged margin 13, thereby assisting in the locking action. As the pin point normally 85 projects from the back of the button (see dotted lines 23, Fig. 4), insertion of the pin point into textile material to which it is to be fastened, such as a coat lapel, can be performed without difficulty and once fastened in place, it is securely and positively locked until purposely removed.

I claim:

1. The combination of a button having an 95 interiorly extending continuous, circular in-turned rear flange thereon, and forming a pin receiving channel, a pin member comprising a portion adapted to be compressed and held under said flange and also comprising a pin portion shorter than a diameter of the circular opening within the flange, said pin portion having a spring tension toward the edge of the button and adapted to be received and held with its point in said channel under the inturned 100 flange in position to form substantially a chord of the circle.

2. As a new article of manufacture, a pin 110 for buttons having a continuous, circular rear marginal flange, forming a pin receiving channel, said pin comprising a substantially part-circular portion for insertion into the channel under the button flange, and a pointed fastening portion shorter than a diameter of the circular opening within 115 the button flange and adapted to form substantially a chord of such circular opening, the two parts joining in a rounded curve, the pointed portion having a spring tension normally holding it away from the first-named portion, and the end of said pointed portion normally extending out of the plane of the first-named portion, and adapted to be positioned to bring its point adjacent to the inner side of said channel under said 120 flange.

3. A button having an inwardly directed flange at the rear thereof and having a pin 125

member secured under said flange, said pin member having a resilient pin portion slightly offset rearwardly from the plane of said flange and adapted to be tensioned to 5 permit securing its end under said flange or removing same therefrom at will for the

purpose of securing the button to or removing same from a garment.

In testimony that I claim the foregoing I hereto set my hand this 11th day of June, 10 1918.

WALTER H. PHELPS.
